NON-REMOVABLE COLLAR STAY

Gilbert O. Driesbach, Robesonia, Pa., assignor to Publix Shirt Corporation, New York, N. Y., a corporation of New York

Application August 2, 1954, Serial No. 447,363

4 Claims. (Cl. 2—132)

The present invention relates to collars, and, more particularly, to novel collar constructions having means incorporated to maintain the collar ends in a non-curling condition.

In accordance with the present invention, a cushion means is provided for a stay. Both the stay and the cushion means are a permanent part of the collar structure. The cushion means of this invention is disclosed herein by way of several modifications.

The primary object of the present invention is to provide a novel collar construction having a permanently incorporated stiffening means.

Another object is to provide a novel stiffening means having a cushion effect to permit laundering without exposing the presence of the cushioning means.

A further object is to provide a novel stiffening means in which the stiffening effect is enhanced by fusing certain of the collar parts together.

A still further object is to provide a novel stay pocket for a collar composed of cushioning layers of material.

Other and more specific objects of the present invention, and advantages thereof, will, of course, become apparent and immediately suggest themselves to those skilled in the art to which the invention is directed from a reading of the following specification in connection with the accompanying drawing in which:

Fig. 1 is a view from the front of a shirt having a collar embodying features of the present invention;

Fig. 2 is a view in plan representing one of the layers or plies of a collar constructed to embody the present invention;

Fig. 3 is a view in plan of a portion of the stay retaining cushion of this invention in one illustrative form;

Fig. 4 is a view in plan of another portion of the cushion to be used with the portion of Fig. 3;

Fig. 5 is a view in plan of a further portion of the cushion to be used with the portions of Figs. 3 and 4;

Fig. 6 is a view in plan illustrating a collar stay suitable for use with the present invention;

Fig. 7 is a view in plan of the assembled cushion;

Fig. 8 is a view in plan of one of the layers or plies having assembled thereto the cushion of Fig. 7;

Fig. 9 is a view in plan of a collar, such as the collar in Fig. 1, showing at one end the unturned unfinished collar portion, and the other end showing the finished results;

Fig. 10 is a view in sectional elevation of the collar of Fig. 9, the section being taken on line 10—10 as viewed in the direction of the arrows;

Fig. 11 is a view in plan, similar to Fig. 2, of a layer or ply for a modified form of the invention;

Fig. 12 is a view in plan, similar to Fig. 8 of the modified form;

Figs. 13 to 16 show the parts of an insert piece also shown in Fig. 12;

Fig. 17 is an assembled view of the insert piece of Fig. 12 in a stage of construction;

2

Fig. 18 shows the completed insert piece of Fig. 17; Fig. 19 is a view in cross section on line 19—19 of Fig. 12;

Fig. 20 is a view similar to Fig. 9 of the modified form of the invention;

Fig. 21 is a view similar to Fig. 11 of a layer or ply for another and further modification of the invention;

Fig. 22 is a view in plan of a piece or strip to be secured to a collar layer;

Fig. 23 is a view in plan of a suitable stay for use with the further modification of the invention disclosed in Figs. 21 to 25;

Fig. 24 is a view similar to Fig. 12 showing parts assembled to a ply of Fig. 21;

Fig. 25 is a view similar to Fig. 20 and discloses a collar embodying the invention in its third disclosed form; and

Fig. 26 is a view in section on line 26—26 of Fig. 25.

Referring for the present to Figs. 1 to 10 of the drawing, there is shown a shirt 1 (Fig. 1) having a collar 3 secured thereto in any suitable and known manner. The collar 3 includes the usual band 18. The shirt 1 is of usual construction. The collar 3 embodies the present invention in one form and the points thereof are permanently stiffened in a novel manner. The stiffening member or stay 14 (Fig. 6) is so mounted in or at each point of the collar 3 that there is a cushion effect. The stay is incorporated in such a way that there is, in effect, a tapering off of the collar insert, thus obviating too pronounced a showing of the insert. This promotes laundering so that the inner structure including the stay is substantially invisible after laundering.

Fig. 7 of the drawing shows the assembled cushion structure which retains the stay 14. The latter is made of a suitable plastic material. For example, it has a suitable width, length and thickness for the type of collar in which it is to be incorporated. The material of the stay 14 may be nylon processed in sheet or strip form by extrusion. This material is washable and has non-breakable and non-kinking features. The stay 14 is cut from the material and is ready for insertion in the collar.

The cushion structure is made up of one ply of soft cloth fabric 8 (Fig. 3), one ply of regular shirting cloth material 10 (Fig. 4), and one ply of a tape 12 (Fig. 5) such as cotton tape. For a collar of the usual presently fashionable width the tape may be about nine-sixteenths of an inch wide. The parts 8, 10 and 12 are held together by two rows of stitching 5 and 7. These rows of stitching form a channel for the stay 14. The stay 14 is located between the tape 12 and the part 8. As shown the part 8 projects beyond the part 10. It will be understood that the stay may be inserted between any two layers or parts so long as concealment is obtained.

The cushion assembly with the stay 14 in place is fastened to the bottom ply 4 of the collar as shown in Fig. 8, in proper position to support the point of the collar. It will be understood, and as shown, that two cushion assemblies are required. The cushion assembly is secured to the ply 4 by spaced rows of stitching 9 and 11 which converge at the point of the cushion assembly. These rows 9 and 11 follow the outline of the part 10, except at the top leaving a free edge for the part 8.

The right hand end of Fig. 9 shows the collar structure prior to turning and finishing. This right hand end shows the exposed ply 4 as it is shown in Fig. 8. Also, the plies 2 and 6 are shown in that order beneath the ply 4. A line of stitching 15 joins the plies 4, 2 and 6. It will be understood that the stitching 15 runs completely around the edge of the unturned collar.

The left hand end of Fig. 9 shows the collar top finished and ready to band, as to the band 18 in Fig. 1.

of the drawing. The entire collar as shown to the right of Fig. 9 is turned inside out, in effect, so that the layer 2 is on top or next to the viewer as seen in Fig. 9 at the left. Next is the liner layer 6 of the stiffer material and then the layer 4. The layer 4 still bears the cushion assembly which lies under the layer 6. A finishing stitch 21 is run around the entire collar.

In the arrangement as described in connection with Figs. 1 to 10, a cushion is provided to give a better finish in pressing. It will be understood that the cushion effect can be obtained by employing various materials or the number of plies within the scope of the description. The projection of the portion 3 and the ply arrangement provide an off-set feature in combination.

The cushion may embody more than two plies and the invention is not limited to the two plies.

Figs. 2 to 11 of the drawing show a modification in which certain of the parts are "fused" together. Fusing is accomplished by the use of a suitable solvent and application of heat and pressure in a suitable press.

Fig. 11 shows, in outline, the collar layers of the collar or collar top. These are 102, the top ply of the collar; 104, the bottom ply of the collar; and 106, the lining of the collar. Figs. 13 to 16 show the parts of the insert piece which is to be mounted to the layer 104. This insert piece comprises one ply of regular shirting 108 (Fig. 13); one ply of regular shirting 110, or piece of tape (Fig. 14); and one ply of lining material made up of cellulose acetate and cotton fibers 112 (Fig. 15). Fig. 16 shows the Nylon stay 114 which may be constructed as described above. These parts are stitched together to form a channel or pocket for the stay 114. The stay 114 lies on top of the part 112 as shown in Fig. 17. The part 110 is folded to embrace the part 112. The assembly, as in Fig. 17, is fused as described above to provide the structure of Fig. 18. The piece 112 is secured in this manner to one folded course or side of the piece 110. A line of stitching 118 joins the parts in Fig. 18.

Fig. 12 shows the assembly of Fig. 18 joined to the layer 104. One assembly is joined to each end of this layer. Fig. 19 is a section showing the relationship of the parts. Fig. 20 corresponds to Fig. 9 described above. In Fig. 20, the left hand end shows the unfinished and unturned collar top. The right hand end shows the finished and turned collar top. In Fig. 20, stitches 122 and 123 join the assembly of Fig. 18 to the layer 104. The layers are joined by the stitches 126. At the right hand end, stitches 128 serve as the finish stitching.

Figs. 21 to 25 disclose a further modification. In this form, all cushioning is provided from the collar lining. Fig. 21 shows the collar top layers 202, 204 and 206 in outline. Fig. 22 shows the tape 212 to be secured to the ply 204. Securing is accomplished by stitching 218 as shown in Fig. 24. Figs. 25 and 26 show the finished collar top in the manner described above. The left hand end of Fig. 25 shows the finished collar top with the finished stitch 222. The right hand end shows the stitch 224 to join the layers 202, 204 and 206. The stay 214 (Fig. 23) is as described above. From what has gone before, the functioning of the collar of Fig. 25 will be apparent. In this modification, the lining layer 206 provides the cushion against laundering effects. Also, the stay 214 lies in a position as shown to give maximum support without being obtrusive in outline.

What is claimed is:

1. A collar construction comprising a bottom ply, cushion means secured to said bottom ply at each end of said collar, each of said cushion means comprising a soft cloth fabric piece seated against said bottom ply and conforming to said end configuration, a piece of regular shirting of lesser area than the soft cloth fabric piece next adjacent said soft cloth fabric piece, and said

cushion means also comprising a strip of tape secured to said soft cloth fabric piece opposite said piece of regular shirting, spaced lines of stitching joining said strip of tape to said soft cloth fabric piece to provide a stay receiving pocket, and lines of stitching securing said assembly to said bottom ply.

2. A collar construction having a selected configuration at each end comprising a top ply, a bottom ply, and a liner ply of stiffer material, cushion means secured to said bottom ply at each end of said collar, each of said cushion means comprising a soft cloth fabric piece seated against said bottom ply and conforming to said end configuration, a piece of regular shirting of lesser area than the soft cloth fabric piece next adjacent said soft cloth fabric piece, and said cushion means also comprising a strip of tape secured to said soft cloth fabric piece opposite said piece of regular shirting, spaced lines of stitching joining said strip of tape to said soft cloth fabric piece to provide a stay receiving pocket, and lines of stitching joining said cushion assembly to said bottom ply, said lines of stitching converging and following the outline of said piece of regular shirting except at the top to leave a free edge for the soft cloth fabric piece inwardly of the end of said collar.

25 3. A collar construction having a selected configuration at each end comprising a top ply, a bottom ply, and a liner ply of cellulose acetate and cotton fibers, cushion means secured to said bottom ply at each end of said collar, each of said cushion means comprising a soft cloth fabric piece seated against said bottom ply and conforming to said end configuration, a piece of regular shirting of lesser area than the soft cloth fabric piece next adjacent said soft cloth fabric piece, and said cushion means also comprising a strip of tape secured to said soft cloth fabric piece opposite said piece of regular shirting, spaced lines of stitching joining said strip of tape to said soft cloth fabric piece to provide a stay receiving pocket, and lines of stitching joining said cushion assembly to said bottom ply, said lines of stitching converging and following the outline of said piece of regular shirting except at the top to leave a free edge for the soft cloth fabric piece inwardly of the end of said collar.

4. A collar construction having a selected configuration at each end comprising a top ply, a bottom ply, and a liner ply of stiffer material, cushion means secured to said bottom ply at each end of said collar, each of said cushion means comprising a soft cloth fabric piece seated against said bottom ply and conforming to said end configuration, a piece of regular shirting of lesser area than the soft cloth fabric piece next adjacent said soft cloth fabric piece, and said cushion means also comprising a strip of tape secured to said soft cloth fabric piece opposite said piece of regular shirting, spaced lines of stitching joining said strip of tape to said soft cloth fabric piece to provide a stay receiving pocket, lines of stitching joining said cushion assembly to said bottom ply, said lines of stitching converging and following the outline of the piece of regular shirting except at the top to leave a free edge for the soft cloth fabric piece inwardly of the end of said collar, stitching securing said top ply, bottom ply and liner together, and finishing stitching around the edge of said collar except at the top thereof to facilitate securing of said collar to a shirt.
